US00D948072S

(12) **United States Design Patent** (10) Patent No.: **US D948,072 S**
Shapiro et al. (45) Date of Patent: ** Apr. 5, 2022

(54) **SHAKER**

(71) Applicant: **Thermo Fisher Scientific (Asheville) LLC**, Asheville, NC (US)

(72) Inventors: **Victor Shapiro**, Oceanside, CA (US); **John M. Staton**, Waltham, MA (US); **Sebastian Henne**, Goettingen (DE)

(73) Assignee: **Thermo Fisher Scientific (Asheville) LLC**, Asheville, NC (US)

(**) Term: **15 Years**

(21) Appl. No.: **29/812,207**

(22) Filed: **Oct. 20, 2021**

Related U.S. Application Data

(62) Division of application No. 29/679,825, filed on Feb. 11, 2019, now Pat. No. Des. 936,238.

(57) **CLAIM**

The ornamental design for a shaker, as shown and described.

DESCRIPTION

FIG. 1 is an isometric view of a shaker according to one embodiment of the present invention;

FIG. 2 is a front elevation view thereof;

FIG. 3 is a right side elevation view thereof;

FIG. 4 is a left side elevation view thereof;

FIG. 5 is a top plan view thereof; and

FIG. 6 is a bottom plan view thereof.

FIG. 7 is an isometric view of a shaker according to a second embodiment of the present invention;

FIG. 8 is a front elevation view thereof;

FIG. 9 is a right side elevation view thereof;

FIG. 10 is a left side elevation view thereof;

FIG. 11 is a top plan view thereof; and,

FIG. 12 is a bottom plan view thereof.

The broken lines in the drawings depict portions of the shaker that form no part of the claim.

1 Claim, 12 Drawing Sheets
